UNITED STATES PATENT OFFICE.

FREDERICK DASSORI, OF NEW YORK, N. Y.

TRUSS.

1,049,813.

Specification of Letters Patent. Patented Jan. 7, 1913.

Application filed August 22, 1911. Serial No. 645,415.

To all whom it may concern:

Be it known that I, FREDERICK DASSORI, a citizen of the United States, and a resident of the city of New York, borough of Brooklyn, in the county of Kings and State of New York, have invented a new and Improved Truss, of which the following is a full, clear, and exact description.

My invention is an improvement in trusses designed for the relief of sufferers from hernia; and so constructed that it will hold any rupture, no matter how old, obstinate or recalcitrant, under all conditions, and without causing the slightest inconvenience to the wearer.

It comprises essentially a pad connected to a belt forming supporting means therefor, the said belt engaging the body of the wearer above the hips; and the pad is connected to the belt by means which give a leverage action to force the same against the hernial tumor without tightening the belt. By this construction the bones of the pelvis are left free and untouched; and practically all the inconvenience of wearing a device of this sort is eliminated.

Reference is to be had to the accompanying drawings forming a part of this specification, in which the same characters of reference indicate the same parts in all the views.

Figure 1 is a perspective view of my improved truss, showing the manner in which the same is worn by the patient; Fig. 2 is a vertical section taken through the belt, showing the manner in which the pad is supported thereby, and the means for applying pressure to the pad by means of a leverage action, to hold the tumor in place without need of tightening the belt which supports the truss; Fig. 3 is a front view of the pad and the controlling means therefor; and Fig. 4 is a side elevation of the pad partly in section, showing the manner in which the pad is joined to the controlling means.

My improved truss comprises an ordinary belt 1, which passes around the body of the wearer and supports the other parts of the truss in proper position. This belt has an end strap 2, which engages a buckle 3, to secure the ends of the belt together around the waist of the wearer at a point above the

hips, as will appear from an inspection of Fig. 1.

The numeral 4 designates a pair of aligned spiral springs, these springs forming part of a single piece of wire 5 of the proper strength and resilience; and the adjacent ends of these springs are separated from each other by a loop 6 formed by bending portions of the wire 5 parallel to each other for a certain distance in passing from one of the spiral springs 4 to the other. This loop 6 forms an operating arm or lever for the pad or cushion 7, which is attached to the wire portions forming the loop 6, by means of a sliding connection 8. This sliding connection 8 may be of any desired or convenient shape, but I have shown it as consisting of a piece of metal bent in the form of a flat tube open at its upper and lower ends so as to give free passage to the wire portions forming the loop 6; and having its opposite sides perforated to permit a screw 9, projecting from a plate 9' forming the back of the pad or cushion 7, to be passed therethrough.

10 is a binding nut engaging the outer end of the screw 9; and when this nut is tightened it presses the opposite or flat sides of the sliding connection 8 together against the plate 9', to make them grip the parallel portions of the wire forming the loop 6, and hold the pad in adjusted position.

Normally, the pad is supported by the belt being fastened to the loop 6 below the spiral springs 4, the loop 6 projecting below the lower edge of the belt a sufficient distance to allow the amount of adjustment required. The two spiral springs 4 will be positioned above the upper edge of the belt a sufficient extent to allow of the required leverage action; and the outer ends of these springs are bent together to form an operating arm 5'. To this operating arm 5' is connected an under strap 11, this under strap passing below the abdomen of the wearer, and being secured to the belt by means of a buckle 12 at the rear thereof.

As shown in Fig. 1, the belt is worn above the hips, and its sole function is to support the pad at such a point that it will rest directly upon the tumor and force it back into the body. The pressure is applied by tight-

ening the under strap 11; and it will be apparent that a pull on the lower end of the arm 5' will stress the alined spiral springs 4 in such a way as to cause the loop 6 to press 5 inward upon the cushion or pad 7. The amount of pressure is of course regulated by giving the proper relative dimensions to the lever arm formed by the parallel portions of wire constituting the loop 6, and 10 the operating arm 5'; and by adjusting the pad up or down along the wire portions forming the loop 6; and it will be apparent that the lever arm formed by the parallel wire portions constituting the loop 6, and 15 the operating arm 5' formed by the wire portions leading from the opposite ends of the alined spiral springs 4, constitute a sort of bell-crank lever, the arms of which have resilient connection with each other through 20 the spiral springs 4, and which is admirably adapted to give the desired result.

From the above it will be apparent that when the belt is once secured around the body of the wearer it does not again have to 25 be touched; and that the degree of pressure applied by the pad or cushion 6 is obtained solely by tightening or untightening the under strap 11. The pressure is a constant, active pressure, owing to the action of the 30 alined spiral springs 4, which will always take up any slack in the strap 11 that might be produced by the movements of the wearer in walking. Hence, all the galling, blistering and cutting into the flesh, which often 35 result in cases where the belt has to be tightened in order to cause the pad or cushion to be pressed against the hernial opening, are entirely avoided. The loop portion of the spring always exerts a gentle pressure 40 through the pad directly upon the affected part. This pressure has a slight upward tendency, forcing the tumor back through the abdominal opening and effecting a cure wherever a cure is possible.

45 I have found that my improved device is equally applicable to inguinal, scrotal or navel rupture, and in all such cases can be worn with the greatest possible amount of ease and comfort.

50 I wish to emphasize the fact that the belt serves merely to support the truss in place, and not to apply pressure to the pad. The pad is pressed against the tumor by tightening the under strap which actuates the lever arm 5'; and thus all the inconvenience 55 which is necessarily produced by trusses in which elastic belts are employed to press the pad against the tumor is eliminated.

Having thus described my invention, I 60 claim as new and desire to secure by Letters Patent:

1. A device of the kind described, comprising a belt, leverage means comprising a pair of converging arms mounted in resili-

ent relation to each other supported by said 65 belt, said belt passing between said arms, a pad or cushion connected to the inner of said arms, and a strap connected to the outer of said arms at one end and to the belt at the other end to operate said leverage means 70 to apply pressure to the pad or cushion, said belt, owing to its location between said arms, serving to hold the pad snugly and to prevent the same from wabbling about the outer of said arms as an axis.

2. A device of the kind described comprising a supporting belt, leverage means comprising a single piece of wire having portions bent parallel to each other to form a U-shaped loop, and then being bent to 80 form alined spiral springs adjacent the ends of said parallel portions, the wire portions leading from the other ends of said spiral springs being bent substantially parallel to form an operating arm, a pad or cushion 85 connected to the parallel wire portions forming the U-shaped loop, and a tightening strap connected to the wire portions leading from the other ends of said springs at one end and to said belt at the other end, to apply pressure to said pad by pulling upon 90 said leverage means, the wire portions forming the loop and the wire portions leading from the other ends of the alined spiral 95 springs making an acute angle with each other, said belt being located between the loop and the portions connected to the tightening strap.

3. A device of the kind described comprising a supporting belt, leverage means 100 comprising a single piece of wire having portions bent parallel to each other to form a U-shaped loop, and then being bent to form alined spiral springs adjacent the ends of said parallel portions, the wire portions 105 leading from the other ends of said spiral springs being bent substantially parallel to form an operating arm, a pad or cushion connected to the parallel wire portions forming the U-shaped loop, and a tightening 110 strap connected to the wire portions leading from the other ends of said springs at one end and to said belt at the other end, to apply pressure to said pad by pulling upon 115 said leverage means, the wire portions forming the loop and the wire portions leading from the other ends of the alined spiral springs making an acute angle with each other.

4. A device of the kind described comprising a belt, leverage means comprising a pair of converging arms supported by said belt, said arms being connected by coiled springs to be mounted in resilient relation to each other, said belt passing between said 120 arms, a pad or cushion connected to the inner of said arms, and a strap connected to the outer of said arms at one end and to the

belt at the other end to operate the leverage means to apply pressure to the pad or cushion, said belt, owing to its location between said arms, serving to hold the pad snugly and to prevent the same from wabbling about the outer of said arms as an axis.

In testimony whereof I have signed my

name to this specification in the presence of two subscribing witnesses.

FREDERICK DASSORI.
